UNITED STATES PATENT OFFICE.

JAMES A. WYNNE, OF POORE'S MILLS, GEORGIA.

RIDING-SADDLE.

SPECIFICATION forming part of Letters Patent No. 270,196, dated January 2, 1883.

Application filed October 31, 1882. (No model.)

To all whom it may concern:

Be it known that I, JAMES A. WYNNE, of Poore's Mills, in the county of Colquitt and State of Georgia, have invented a new and Improved Spring-Seat Saddle, of which the following is a full, clear, and exact description.

My invention relates to improvements in spring-seat saddles; and it consists in the peculiar construction and arrangement of parts, as hereinafter fully described, and pointed out in the claim.

Reference is to be had to the accompanying drawings, forming part of this specification, in which similar letters of reference indicate corresponding parts in all the figures.

Figure 1 is a perspective view of my improved spring-seat saddle. Fig. 2 is a plan view of the bottom seat of the saddle, the top seat being removed. Fig. 3 is a plan view of the under side of the top spring-seat. Fig. 4 is a cross-sectional elevation of my improved spring-seat saddle. Fig. 5 is an enlarged detail longitudinal elevation of the same on the line x x ; Fig. 4.

The saddle is composed of the usual saddle-frame or bottom seat, A, and the top seat, B, which is above the seat A, and is supported by a series of spiral springs, C, preferably four, resting on the lower seat, A. The ends of the springs are firmly secured in the top and bottom seats, A B, respectively, and the two front springs, C, as well as the two rear springs, are connected by metal straps or bands D, secured transversely to the under

side of the top seat, B, at the front and rear. 35 The springs C each surround a pin or peg, E, which pins are secured on the bottom seat, A, and project into apertures F in the top seat, B, for the purpose of permitting the top seat to move up and down.

The bottom seat, A, is provided with cushions and pads in the usual manner, and the rider sits on the top seat, which is altogether supported by the springs C, which counteract the movements of the horse and ease the rider 45 as well as the horse, as the weight of the rider, does not act directly on the horse.

The saddle can be trimmed and completed in the usual manner.

The spiral springs C are to be made of steel, 50 and any suitable number of springs may be provided.

Having thus described my invention, what I claim as new, and desire to secure by Letters Patent, is—

In a saddle, the combination, with the bottom seat, A, provided with the pins E, projecting from its upper surface, of the top seat B, provided with apertures or recesses, F, the springs C, secured to both the top and bottom 60 seats and surrounding their respective pins, substantially as and for the purpose set forth.

October 28, 1882.

JAMES A. WYNNE.
